INVENTOR

BY *Victor J. Evans*

ATTORNEY

UNITED STATES PATENT OFFICE.

ADELARD JOSEPH DUBEE, OF GLENS FALLS, NEW YORK.

SASH-TIGHTENER.

1,374,067.

Specification of Letters Patent. Patented Apr. 5, 1921.

Application filed July 23, 1920. Serial No. 398,348.

To all whom it may concern:

Be it known that I, ADELARD JOSEPH DUBEE, citizen of the United States of America, residing at Glens Falls, in the county of 5 Warren and State of New York, have invented new and useful Improvements in Sash-Tighteners, of which the following is a specification.

This invention relates to improvements 10 in sash tighteners, and the principal object is to provide a device of this nature which will be simple of construction, cheap to manufacture and effective for the purpose for which it is designed.

15 To this end the invention consists in certain novel constructions, combinations and arrangements of parts, the essential features of which are fully set forth in the accompanying description and claim and which 20 are illustrated in the accompanying drawing consisting of one sheet, in which:—

Figure 1 is a vertical sectional view of a window with my improvement in place.

Fig. 2 is an enlarged detail view of the 25 device *per se* detached.

Figs. 3 and 4 are views similar to Fig. 2, but illustrating modified forms of the invention.

Like characters of reference refer to like 30 parts in all views.

This invention contemplates the providing of a device which may be permanently attached to the window jamb and moved into coöperation with the window sash for 35 preventing rattling, or in the winter time for keeping it tightly in place.

Referring more particularly to the drawings, 1 represents the sill of a window and 2 represents the blind stops which are at the 40 exterior side of the upper sash, said upper sash being shown at 3. The lower sash is shown at 4, and between the two sashes are the usual parting strips 5. The inside stop and jamb are represented by 6 and 7, 45 respectively.

Secured to the jamb 7 by a screw 8 which passes through a rubber washer 9 is a member 10, the free end of which is internally

threaded in the form shown in Figs. 1 and 2. A presser member 11 is provided with 50 a presser foot 12, a finger piece 13, and a threaded portion 14. The threaded portion 14 screws in the free end of member 10.

Normally when not in use, the device may be swung down to a vertical position on 55 the jamb. When it is to be used, the device is moved to a horizontal position and member 11 is screwed out until foot 12 contacts the sash and presses it firmly against the blind stop or the parting strips according to whether it is the upper or lower sash which is operated against.

In the form shown in Fig. 3, the ends of members 10 and 11 are threaded and are both screwed into a sleeve 15. 65

In the form shown in Fig. 4, a turn-buckle 16 is combined with members 10 and 11.

If made for use on the upper sash, the members 10 and 11 will be made longer than if for use against the lower sash. 70

While I have described what I deem to be the most desirable embodiments of my invention, it is obvious that many of the details may be varied without in any way departing from the spirit of my invention; 75 and I do not limit myself to the exact details of construction herein set forth nor to anything less than the whole of my invention limited only by the appended claim.

What I claim as new and desire to secure 80 by Letters Patent is:—

The combination of a member provided in one end with an aperture for permitting the passage of a screw or the like for pivotally securing said member to a window 85 frame and provided at its opposite end with a threaded portion, a presser member provided with a threaded portion said members being held in relative adjustment by means of said threaded portions, and manipulative 90 means for effecting relative adjustment of said members.

In testimony whereof I have affixed my signature.

ADELARD JOSEPH DUBEE.
